UNITED STATES PATENT OFFICE.

LEWIS A. HOWE, OF BOSTON, MASSACHUSETTS.

STOP MECHANISM FOR PLUNGERS.

SPECIFICATION forming part of Letters Patent No. 639,175, dated December 12, 1899.

Application filed May 15, 1899. Serial No. 716,856. (No model.)

To all whom it may concern:

Be it known that I, LEWIS ALVIN HOWE, of Boston, in the county of Suffolk and State of Massachusetts, have invented a new and useful Stop Mechanism for Plungers, of which the following is a specification, reference being had to the accompanying drawings, making a part hereof, in which—

Figure 1 is a side elevation of a machine embodying my invention. Figs. 2 and 3 are front elevations of the head of the machine, showing the parts in different positions. Figs. 4 and 5 are sections on line 4-4 of Fig. 2, showing the parts in different position. Fig. 6 is a detail described below.

A variety of machines have long been known which when started stop automatically after one operation, and my invention relates to machines of this class in which a plunger or other reciprocating member is required to stop automatically after doing its work and in position for repeating its operation.

In the drawings I have shown my invention embodied in a stamping-machine in which a work-support A sustains the article to be stamped under the pressure of a die B', which is carried by plunger B, so that when the plunger B is forced toward work-support A the article—as, for example, a shoe-sole—will be pressed between the die B' and the support A at each downward stroke of plunger B, the die B' leaving its impression on the shoe-sole.

My new mechanism for reciprocating plunger B consists of a reciprocating member D, preferably in the form of a lever, and a connector F, which is moved to bring it into operative position through an arm F', which arm is automatically moved by the operating stroke of the plunger to release connector F and allow a spring f or equivalent device to carry a connector F out of operative position—that is, the motion of lever D about its fulcrum d⁰ has no effect upon plunger B until plunger B and lever D are connected by connector F, and when so connected the motion imparted to plunger B by D automatically releases connector F from control of arm F' and allows connector F to move out of engagement with lever D as lever D makes its return stroke. The return stroke of plunger B is caused by spring b or some equivalent device. This mechanism, which is my inven-

tion, is far simpler and more compact and certain in operation than any other for any similar purpose known to me.

55

Lever D or its equivalent is actuated by pitman d, eccentric d', and shaft d², as will be plain from the drawings, and while the power may be applied directly to shaft d² it is in most cases desirable to gear shaft d² to 60 a rapid-running counter-shaft d³, especially in machines in which power is transmitted through lever D. The counter-shaft d³ is hollow or in the form of a sleeve on a stud d⁴, which stud projects from a bracket d⁵, secured 65 to the frame of the machine, and this counter-shaft is driven by fast and loose pulleys or a friction-clutch in the usual way.

The operation is as follows: The operator, having placed the work on the work-support 70 A, depresses treadle a, and thereby, through treadle-rod a', bell-crank lever a², and slide f', forces arm F' against a pin f², fast to connector F, thereby moving connector F into its operative position between lever D and 75 plunger B, (see Fig. 5,) so that as lever D makes its operating-stroke it carries connector F and plunger B with it, forcing die B' against the work on support A; but as connector F is thus moved its pin f² engages 80 cam-surface f³ on arm F' and swings arm F' to one side, (see Fig. 3,) and spring f moves connector F to its inoperative position (see Fig. 4) as soon as lever D begins its return stroke and ceases to press connector F 85 against plunger B, and lever D oscillates without affecting plunger B until treadle a is released, which allows slide f' to return to the position shown in Fig. 4, whereupon arm F' swings over pin f² in position to again act 90 on connector F through pin f², when the treadle is again depressed.

What I claim as my invention is—

1. In combination a reciprocating body, a plunger, a connector which in one position 95 connects the reciprocating body and the plunger together; a swinging arm to move the connector positively into operative position against the force of a spring; that spring; a cam on the swinging arm; and a projection 100 on the connector adapted to engage the cam and move the arm while the reciprocating body and the plunger are making their operating stroke to thereby automatically release

the connector from the control of the arm, substantially as described.

2. In combination reciprocating body D; plunger B; connector F; arm F'; slide f' to which arm F' is pinned; an inclined plane on arm F'; and a device on connector F to engage with the inclined plane on arm F' and swing it to one side to release connector F

from control of arm F', as connector F and plunger B move together; all substantially as and for the purpose specified.

LEWIS A. HOWE.
